UNITED STATES PATENT OFFICE.

DAVID LARSON, OF YONKERS, NEW YORK, ASSIGNOR TO OTIS ELEVATOR COMPANY,
OF JERSEY CITY, NEW JERSEY, A CORPORATION OF NEW JERSEY.

SAFETY SLOW-DOWN AND STOP MOTION FOR ELECTRIC ELEVATORS.

982,074.

Specification of Letters Patent. Patented Jan. 17, 1911.

Application filed May 18, 1909. Serial No. 496,810.

To all whom it may concern:

Be it known that I, DAVID LARSON, a subject of the King of Sweden, residing at Yonkers, in the county of Westchester and State 5 of New York, have invented a new and useful Improvement in Safety Slow-Down and Stop Motions for Electric Elevators, of which the following is a specification.

My invention relates to a safety slow-down, 10 and stop motion device which is adapted to be used in connection with electric elevators, and one of the objects of the invention as used in such connection is to provide means for slowing down the speed of the elevator 15 car before either limit of the travel of the said car is reached.

Another object is to stop the car automatically at either limit of travel thereof without operative attention thereto.

20 A further object is to prevent the operation of the slow-down device unless the speed of the elevator car is too great.

For the attainment of these ends and the accomplishment of other new and useful 25 objects, my invention consists in the features of novelty in the combination and arrangement of the several parts hereinafter more completely described, and claimed in the appended claims.

30 In the accompanying drawings, Figure 1 illustrates my invention as applied to an elevator control system in connection with the operating switch thereof; Fig. 2 shows a modification of the same in connection with 35 the reversing switches.

Limit switches as ordinarily employed at present, are located near the limits of travel of the car and allow the car and driving mechanism to continue to run at full speed 40 until the limit switch is opened, which is intended to stop the car and the operating mechanism without damage to the elevator. If the elevator is heavily loaded on a down trip, the tendency, when coming down at full 45 speed, is to continue even after the limit switch has been opened, and if there is not sufficient free travel left for the car to stop, it will strike the bottom at nearly full speed, thereby causing damage and injury. The 50 same difficulty may be experienced at the top limit of travel. My invention is adapted to do away with this threatened danger entirely, by automatically slowing down the elevator car and the operative mechanism 55 before the limit switches are reached; if the

speed is not too high, when the slow-down positions are reached, the slow-down apparatus will not be required, and hence will not be operated.

Referring to Fig. 1, traction sheaves 13, 14 are provided in conjunction with the motor M, and the rope 15 passes around these sheaves and over the pulleys 11, 12, suspending the elevator car C and the counterweight W in the ordinary way. The motor is connected to the mains (+ and -) through the main fuses F, knife switch S, operating switch P, wires 16, 17, reversing switch R or R', motor leads 18, 19, to the motor M; the motor field is connected to the wires 16 and 17 through the field lead wires 20, 21, and the brake B is connected directly to the motor leads 18, 19 through the wires 22, 23; the brake is therefore energized whenever the motor M is actuated or in operation.

The car switch K is of the ordinary type in which, when a hand lever 26 is turned to the left of a central position, the energizing coil 25 of the reversing switch R' is energized, and when turned to the right of the central position, the energizing coil 24 of the other reversing switch R is energized. In the central position, neither coil 24 nor 25 is energized, the motor leads 18, 19 are not connected to the supply mains, and the motor 55 M receives no current.

The speed governor G is operated by the rope 27 which is connected to the car C in any well known manner, and a switch 28 is arranged in any convenient way to be opened 90 by the governor G when the speed of the governor reaches a predetermined limit.

Attached to the elevator car C is a projecting device 33 which is provided with an inclined projection or groove 34. The 95 switch levers 29, 30 are located at any desired places along the hoistway of the elevator car, preferably near the limit of travel thereof, and the rollers 31, 32 on the levers are adapted to be engaged by the groove 34 to turn the corresponding lever when the car C approaches the lever. The other ends of the levers 29, 30 are provided with contacts 35, 36 which make connection with suitable fixed contacts 37, 38; these connections being 100 broken when the levers 29, 30 are engaged. These switch levers 29, 30 are also acted upon by coil springs 39, 40, respectively, which tend to maintain the lever contacts 35, 36 in position against the said fixed contacts 110

37, 38. The stops 41, 42 prevent the levers from turning too far.

The operating switch P is automatically held in place by current flowing in the coil 44, and released when the current ceases to flow therein. The core of the coil 44 is attached to a hand lever H which is pivotally mounted by the pin 56, and is provided with a stop 55 for limiting the fall of the lever H 10 and the core 52 of the coil 44. The hand lever H is provided so that the operating switch P may be manually operated, when so desired.

The car safety switch 43 and the two switches controlled by levers 29, 30 are all in series, and the three switches in series are parallel connected with the governor switch 28. The operating switch holding coil 44 is in the circuit with the said switches, so that 20 the current passing through the coil 44, must go through the switches too. When one of these switches is automatically opened, or the car safety switch 43 is manually opened at the same time the governor switch 28 is 25 open, the circuit through the operating switch holding coil 44 is broken. These circuits are traced as follows: from the positive main through fuse F, switch S, operating switch P, wires 16 and 45; then through 30 wire 46, governor switch 28, wire 47, to wire 51, and from wire 45 through wire 48, switch contacts 37, 35, wire 49, switch contacts 38, 36, wire 50, switch 43, to wire 51; thence through the operating switch coil 44, 35 wires 53, 54, 17, operating switch P, manual switch S, fuse F, to the negative (—) main. From this it is seen that the operating switch coil 44 will receive current unless both the governor switch 28, and one of the 40 three switches in series are open at the same time. That is, the speed of the elevator car C must be sufficient to cause the governor switch 28 to be open at the same time that one of the other switches is manually or 45 automatically opened. This will break the circuit through the operating switch holding coil 44, and cause the operating switch P to be automatically opened to cut off the current supply to the motor M.

50 Fig. 2 shows a similar application of my invention, with the added feature that the speed of the elevator car is arrested before the limit switches are reached, and by the operation of the latter, the driving mechanism and the elevator car are abruptly stopped. The reference characters employed in describing the various features of Fig. 1 are used to designate the same portions in Fig. 2. It is therefore deemed 55 necessary to explain only the points of difference of the latter figure.

The circuit through the operating switch coil 44 is closed through the car safety switch 43' and the limit switches 62, 63, 60 which are mechanically opened by a device

66 suitably placed on the car C to engage the tips 64, 65 of the limit switch levers 63 and 64. This circuit may be traced from the positive main through the fuse F, switch S, operating switch P, wires 16, 67, switch 70 62, wire 68, safety switch 43', wire 69, switch 63, wire 51, operating switch coil 44, wires 53, 17, operating switch P, switch S, fuse F, to the negative main. When either limit of travel of the elevator car C is reached, the 75 corresponding limit switch 62 or 63 is opened thereby opening the operating coil circuit, which causes the operating switch P to open, and break all current connections to the motor M.

The breaking switch 60 is closed by current flowing in the coil 59, and the object of the said switch 60 is to effect the slow-down of the motive mechanism and the elevator car C before the operation of one of the limit switches 62 or 63. Current flowing in the magnet coil 59, also flows through the governor switch 28, and the two slow-down switches 29 and 30. The two switches 29, 30 are in series, and both in parallel with the governor switch 28. These circuits are traced from the positive wire 16, through wire 61, contact 70, winding 59, to wire 45, where the circuit divides, part passing through wire 47, governor switch 28, wire 46 95 to wire 58, and the remainder passing through wire 48, contacts 37, 35, wire 49, contacts 38, 36, wires 50, 57 to wire 58, from whence it passes to the negative wire 17. This circuit can be closed only when the 100 operating switch P is closed, and is opened when the governor switch 28 and one of the slow-down switches 29 or 30 is open at the same time.

The reversing switches N and N' are 105 operated from the car switch K by the movement of the hand lever 26, but are prevented from operating unless the breaking switch 60 is closed. These reversing switches N, N', are provided with the auxiliary contact switches n, n', which are adapted to 110 close a circuit through the windings of the brake B. Resistance r is provided to limit the current supplied to the brake winding in such a way that the brake B will not be 115 applied with its full strength unless the breaking switch is opened. When the motor M is in operation with the reversing switch N closed, the energizing circuit through the winding of the brake B is traced from the 120 main lead wire 16 through wire 61, contacts 70, 71 of the breaking switch 60, wire 72, auxiliary switch n, wires 74, 22, through the brake winding, thence through wires 23, 20 to the other main lead wire 17. When, 125 however, the reversing switch N is opened by the operation of the car switch K, a circuit which includes the resistance r, is closed through the brake winding. This circuit is completed through the wire 73, and the 130

resistance r , instead of through the contact switch n , and wire 74. The current is so restricted by the resistance r that only a sufficient current flows to apply the brake B gently. This slows down the motor M, so that when either limit switch 62 or 63 is opened, thereby breaking the circuit through the operating switch coil 44, the operating switch P opens, and the brake B is fully applied to stop the motor M.

By means of this invention it is evident that the breaking switch 60 will be automatically opened only when the speed of the elevator car C is excessive at the time when either of the slow-down switches 29 or 30 is operated, for in this event the governor switch 28 is also open and the circuit through the breaking switch coil 59 is opened. When the elevator car C and the driving mechanism are under the control of the car operator, and the speed is not too great, it is not necessary that the safety slow-down apparatus shall be operated.

It is to be understood that the slow-down switches may be located along the elevator hatchway at any desired place or places, so that the motion of the car may be automatically arrested if the speed is too high when the car engages a slow-down switch. The preferred location of these switches is near the limits of travel of the elevator car, but occasions may arise where it would be convenient or advantageous to employ them at other places. The elevator car is thus protected from the inattention of the operator and from accidental speeding of the car, so that there is no danger that the car will be traveling at too great a speed when either of the limit switches is opened.

I desire not to be limited to the exact construction, combination and arrangement as herein set forth, as it is evident that various alterations may be made by those skilled in the art without departing from the principles of my invention, but

What I claim and desire to secure by Letters Patent of the United States, is:—

1. In a safety device for electric elevators, the combination of two switches parallel connected, a circuit breaking device in circuit therewith operative to open the parallel connected circuit, and means whereby the said circuit breaking device opens only when both switches are opened.

2. In a safety device for an electric elevator, the combination of two switches parallel connected, and a circuit breaker operative to slow down the elevator when both switches are open at the same time.

3. In an electric safety for elevators, the combination of a plurality of switches in series, a single switch parallel connected therewith, a device in circuit with said parallel circuits operative to slow down the elevator when the single switch and one of

the series switches are open at the same time.

4. In an electric safety for elevators, the combination of switches in series, a single switch parallel connected with the first named switches, a circuit breaking switch, means for automatically causing the circuit breaking switch to open only when the single switch and one of the series switches are open at the same time, and means whereby the elevator is slowed down when the circuit breaking switch is opened.

5. In a safety device for elevators, the combination of a governor switch, switches in series parallel connected with the governor switch, an electro-magnetic switch device in circuit with the parallel connected switches, means for causing the switch device to open only when the governor switch and one of the series switches is open at the same time, and means whereby the speed of the elevator is arrested when the said switch device is operated.

6. In a safety device for an elevator, the combination with an elevator car, of a driving motor therefor, a governor switch automatically operated by the elevator car to open when the speed thereof is too high, limit switches in series and parallel connected with the governor switch, a breaking switch held normally in closed position by current which flows through the parallel connected circuits and which is automatically operative to break current connections to the driving motor when the governor switch and one of the limit switches are open at the same time.

7. In a safety device for an electric elevator, the combination of an elevator car, a driving motor therefor, an automatic governor switch, switches connected in series, means in connection with the elevator for automatically opening the said switches, an electro-magnetic switch maintained in a closed position by current flowing through the governor switch or the series switches, circuit connections whereby the electro-magnetic switch is opened only when one of the series switches and the governor switch is open at the same time, and means operative to retard the motor when the said electro-magnetic switch is opened.

8. In an elevator safety device, the combination with an elevator car, of switches located along the elevator hatchway and connected in series, an automatic governor switch, means in connection with the elevator car for operating the series connected switches, and means whereby the elevator car will be automatically slowed down when the governor switch and any one of the series connected switches are open at the same time.

9. In an elevator safety device, the combination of an elevator car, switches adapted

- to be engaged by the car and located at any desired places along the elevator hatchway, an automatic governor switch, and means whereby the elevator car is automatically slowed down near any one of the switches engaged by the car when the governor switch is open at the same time the said switches are engaged by the car.
10. The combination with an elevator car, of a driving motor therefor, slow-down switches, limit switches operative to stop the motor, an automatic governor switch, and means associated with the slow-down and governor switches whereby the motion of the elevator car is automatically arrested when the speed is too high, before the limit switches are operated to stop the motor and the elevator car.
11. The combination with an elevator car, of a driving motor therefor, slow-down switches in series, a governor switch parallel connected therewith, limit switches, an operating switch, means for automatically opening the operating switch to stop the motor, and means for operating the slow-down and governor switches to effect a reduction in speed of the elevator car and the motor before the operating switch is automatically opened.
12. The combination with an elevator car, of a motor for moving the car, slow-down switches and limit switches adapted to be opened by the movement of the car, an automatic governor switch parallel connected with the slow-down switches which are in series, a breaking switch normally held in closed position by current which also flows through the said parallel circuit, means associated with the breaking switch for slowing down the elevator car and motor, and means for abruptly breaking the circuit connections of the motor.
13. The combination with an elevator car, of a motor for moving the car, slow-down switches, a governor switch, a breaking switch which opens when the governor switch and a slow-down switch are open at the same time, an operating switch, reversing switches operable manually from the elevator car when the breaking switch is closed, and limit switches and a car safety switch in series with the operating switch holding coil for abruptly stopping the motor and the elevator car when the speed thereof is too high.
14. The combination with an elevator car, of a motor for moving the car, slow-down switches, a governor switch, a breaking switch which opens when the governor switch and a slow-down switch are open at the same time, an operating switch, a car switch, reversing switches normally operable from the car switch, means for causing the breaking switch automatically to open and to reduce the speed of the motor and the elevator car when the speed is too high, and means for manually or automatically opening the operating switch.
15. The combination with an elevator car, of a motor for moving the car, slow-down switches, a governor switch, a breaking switch which opens when the governor switch and a slow-down switch are open at the same time, means for automatically slowing down the car when the breaking switch opens, a car controller-switch, and reversing switches operable from the controller switch.
16. The combination with an elevator car, of a motor for moving the car, slow-down switches, a governor switch, a breaking switch which opens when the governor switch and a slow-down switch are open at the same time, a car controller-switch, reversing switches operable from the controller switch, a brake, a resistance, and means for inserting the resistance in the brake winding circuit to prevent the instantaneous application of the brake at full strength when the controller switch is operated to open a reversing switch.
17. The combination with an elevator car, of a motor for moving the car, slow-down switches, a governor switch, a breaking switch which opens only when the governor switch and a slow-down switch are open at the same time, reversing switches, a car switch for manually controlling the operation of the reversing switches, an electrically controlled brake, resistance which is in circuit with the brake winding when the breaking switch is closed, and means for short-circuiting the resistance when a reversing switch is closed.
18. The combination with an elevator car, of a motor for operating the car, a car controller-switch, reversing switches operated by the movement of the controller-switch, an auxiliary contact switch in connection with each reversing switch and simultaneously operable therewith, an electrically operated brake, resistance adapted to be inserted in the brake winding circuit; and means whereby the closing of a reversing switch short-circuits the resistance thereby energizing the brake to release the motor.
19. The combination of an elevator car, an operating motor therefor, slow-down switches and a governor switch parallel connected, an operating switch, limit switches and a car safety switch in series with the operating switch holding coil, means for automatically operating the parallel connected switches to reduce the speed of the car, and means associated with the safety switch in the car for manually effecting the opening of the operating switch to stop the motor at any desired time.
20. The combination of an elevator car, a governor switch, slow-down switches con-

ected in series and in a parallel circuit with the governor switch, a device in connection with the car for automatically opening the slow-down switches, and means whereby the motion of the elevator car is automatically arrested whenever the speed thereof is exceeding a predetermined limit at the same time one of the slow-down switches is opened.

21. The combination of an elevator car, slow-down switches located along the elevator hoistway, a governor switch parallel connected with the slow-down switches,

means associated with the elevator car for engaging a slow-down switch and operative to effect the slowing down of the elevator car when the speed thereof is too high at any predetermined place.

In testimony whereof, I have signed my name to this specification in the presence of two subscribing witnesses.

DAVID LARSON.
